CLAIM

We claim the ornamental design for a sample deck for selecting a covering for an architectural opening, as shown and described.

DESCRIPTION

FIG. 1 is a front isometric view of a sample deck for selecting a covering for an architectural opening.

FIG. 2 is a rear isometric view thereof.

FIG. 3 is a front elevation view thereof.

FIG. 4 is a rear elevation view thereof.

FIG. 5 is a bottom plan view thereof, the top plan view being a mirror image thereof.

FIG. 6 is a left side elevation view thereof, the right side elevation view being a mirror image thereof; and,

FIG. 7 is a cross-sectional view thereof taken along line 7-7 in FIG. 3.

(Continued)

The broken lines illustrate portions of a sample deck for selecting a covering for an architectural opening that form no part of the claimed design.
